Inventor:
Adolph Sanders
By his Attorney
Geo. W. Math

UNITED STATES PATENT OFFICE.

ADOLPH SANDERS, OF NEW YORK, N. Y.

CHAIR.

No. 918,706.

Specification of Letters Patent. Patented April 20, 1908.

Application filed May 11, 1908. Serial No. 432,062.

To all whom it may concern:

Be it known that I, ADOLPH SANDERS, a citizen of the United States, residing in the borough of Manhattan, city, county, and 5 State of New York, have invented certain new and useful Improvements in Chairs, of which the following is a specification.

My invention is designed to afford a simple but effective folding chair, which may 10 be used either as an ordinary single seat chair, or unfolded to form a settee accommodating two persons. Thus unfolded my chair is also adapted for use as a bench or support for various articles for domestic use, 15 as clothes baskets &c.

The invention consists in the construction and arrangement of parts hereinafter described and claimed specifically.

In the accompanying drawings, Figure 1, 20 is an elevation of the back side of my improved chair; Fig. 2, a vertical section on plane of line 2—2—Fig. 1; Fig. 3, a top view of the chair unfolded; Fig. 4, a vertical section upon plane of line 4—4—Fig. 3; 25 Fig. 5, is a sectional detail upon plane of line 5—5—Fig. 3; Fig. 6, is a similar view showing the position of the extension bars when retracted; Fig. 7, is a sectional detail upon plane of line 7—7—Fig. 3.

30 The base B is provided with the usual chair legs b, b, and cross bars b', b', and may be of any ordinary or desired construction.

To the front edge of the base B, is pivotally connected the seat C, the hinge leaves 35 l, l, being preferably situated in recess b², and c, formed for their reception in the base B, and the seat C, respectively, in which recesses the hinge leaves l, l, are held by screws, pins or dowels d. A pintle p, connects the overlapping ends of the hinge leaves l, l. By this arrangement the hinges are protected and concealed, and a substantial and finished structure attained.

Connected to the rear edge of the base B 45 by hinges h, h, is a yoke Y, the cross member y, of which fits over a rear extension c', on the seat C when the latter is folded over on the base B as shown in Figs. 1 and 2, thus locking the seat in position on said base B. 50 When the yoke is turned back and down as in Figs. 3, 4 and 5, the seat C is free, so that it may be swung forward and over until its otherwise under surface c², coincides with and is in the same plane as the upper surface 55 b'', of the base B, as shown in Fig. 3. In this position the seat C, is supported by

the base on one side and by the back rest c² on the other,—said back rest c² being so proportioned as to correspond with the legs b, on the base B and act in conjunction therewith. 60

In order to relieve the pintle p, from strain when the device is thus extended for use as a bench or settee, I provide extension bars E, E, the forward ends e, e, of which are projected under the seat C immediately beneath said pintle as clearly illustrated in Fig. 4. The forward ends e, e, of the said extension bars E, E, are supported in 65 sockets b³, b³, for their reception in the under structure of the base B.

The rear extremities of the extension bars are suspended on rock levers R, R, pivoted to the base B (see Figs. 5 and 6). The lower arm of each rock lever R, is formed with a 75 slot r, into which a stud e', on the adjacent extension bar protrudes. The upper arm of each rock lever R is also formed with a slot r', into which protrudes a stud y', on the yoke Y. As a result of this construction the 80 release of the seat C by the act of turning the yoke Y, back and down rocks each lever R from the position shown in Fig. 6, to that shown in Fig. 5, in which latter it will be 85 seen that the forward end e, of the extension bar E extends beyond the pintle above, on that side and relieves it from the strain to which it would otherwise be subjected during the use of the device, as a settee, bench, 90 stand or table.

When the seat C is again folded over upon the base B the act of locking it in position thereon by means of the yoke Y retracts the extension bars E, so that their forward ends e, are withdrawn within the front line of the 95 base B as shown in Figs. 2 and 6.

What I claim as my invention and desire to secure by Letters Patent is,

1. A folding chair consisting of a base provided with legs, a seat pivotally connected at its front edge to the front edge of said base and formed with a back rest adapted to act as a support for the seat when the latter is extended in the same plane as the base, a yoke piece hinged to the rear edge of the base, and adapted to engage with a projection on the seat, and an extension bar on the underside of said base connected with and actuated by said yoke piece, for the purpose described. 100

2. A folding chair consisting of a base provided with legs, a seat pivotally con- 105

nected at its front edge to the front edge of said base and formed with a back rest adapted to act as a support for the seat when the latter is extended in the same plane as the base, a yoke piece hinged to the rear edge of the base, and adapted to engage with a projection on the seat, and a plurality of ex-

tension bars connected and actuated by said yoke, for the purpose described.

ADOLPH SANDERS.
